CLAIM

The ornamental design for a pedalless bicycle frame, as shown and described.

DESCRIPTION

FIG. 1 is a left side elevational view of a pedalless bicycle frame showing my new design, the undisclosed right side being a mirror image;

FIG. 2 is a partial side perspective view thereof, broken away for clarity of disclosure;

FIG. 3 is a left side elevational view of a second embodiment thereof, the undisclosed right side being a mirror image;

FIG. 4 is a partial side perspective view thereof, broken away for clarity of disclosure;

FIG. 5 is a left side elevational view of a third embodiment thereof, the undisclosed right side being a mirror image; and,

FIG. 6 is a partial side perspective view thereof, broken away for clarity of disclosure.
